RECESSED LIGHTING EQUIPMENT

Kurt Franck and Vearl Wince, Newark, Ohio, assignors to Holophane Company, Inc., New York, N. Y., a corporation of Delaware

Application February 16, 1946, Serial No. 648,131

10 Claims. (Cl. 240—51.11)

1

The present invention relates to recessed lighting equipment and is more particularly directed toward lighting equipment adapted to be recessed in hung or suspended ceilings.

The present invention contemplates lighting equipment for these purposes adapted to be made up in single units of substantially lamp length so that it can be used as a single lamp length fixture or assembled with other similar units so as to provide continuous lighting equipment.

According to the present invention each lighting fixture unit employs a sheet metal reflector having transverse stiffening means adapted also to cooperate with the supports for the reflector, and longitudinal stiffening means which form external finishing strips for the fixture as well as supports for the light transmitting cover. A further object of the invention is to provide suitable yokes or bridging members, two of which may be used with each unit length of lighting equipment and arranged so that the same yoke or bridging member may be used with various types of hung ceiling constructions.

A further object of the invention is to design the fixture and yokes so that when a number of units are connected together end to end, one can employ one bridging member or yoke carried by one unit length for additionally supporting the adjacent end of another unit length of fixture.

Other and further objects will hereinafter appear as the description proceeds.

The accompanying drawings show, for purposes of illustrating the present invention, an embodiment in which the invention may take form, it being understood that the drawings are illustrative of the invention rather than limiting the same.

In these drawings:

Figure 1 is a side elevational view on a small scale illustrating a typical continuous installation;

Figure 2 is a vertical sectional view on an enlarged scale showing one end of a unit or installation;

Figure 3 is a side elevational view with parts in section illustrating the other end of the unit or installation;

Figure 4 is a cross-sectional view taken on the line 4—4 of Figure 2;

Figure 5 is an exploded view illustrating various parts employed in a single unit;

Figures 6 and 7 are diagrammatic perspective views illustrating additional modes of support;

Figure 8 is a fragmentary sectional view on the line 8—8 of Figure 9; and

2

Figure 9 is a fragmentary elevational view to show a detail.

Each unit employs a sheet-metal reflector 10. This reflector has a comparatively wide flat top portion 11, downwardly sloping upper side portions 12—12, and lower slightly converging portions 13—13. The flat upper portion is provided with a long central opening 14 which receives a downwardly opening sheet-metal box 15 adapted to accommodate a multiple fluorescent lamp ballast 16'. The box and reflector member are welded together. Transverse reinforcements 16 in the form of suitably-bent upwardly-opening steel channels are welded to the top and upper side portions of the reflector member 10. These reinforcements are located between the ends of the box 15 and the ends of the fixture and may conveniently be spaced in the order of 5 inches from the ends of a 4 foot fixture.

20 The lower edges of the reflector member are flanged outwardly as indicated at 17 and longitudinally stiffening strips 18 are welded to the edges of the reflector stamping, or the housing and ceiling flange may be integral as indicated at 17' and 18', Figure 8.

The reflector stamping carries at each end cross-straps indicated at 19 and 20, these straps being secured in place by screws indicated at 21. The strap 19 carries fluorescent lamp holders 22, 30 three of which are shown in the present case; also three starter sockets 23. The starters 24 extend through openings in the strap 19. The strap 20 similarly carries three lamp holders 22'. The length of the reflector 18 is such that the 35 lamp holders are spaced properly for the lamps intended.

The wiring of the fixture is readily accomplished by connecting wires such as indicated at 25 from the ballast to the lamp sockets and interconnecting the lamp sockets and starters by other wires according to standard and well known circuit arrangements. A two-lamp circuit or three-lamp circuit may be employed. These wires are held up by sheet-metal hook-shaped members indicated at 26.

The cross-straps 19—20 carry screws 27 which are adapted to receive a cover plate 28. This cover plate is held up by thumb nuts 29 and closes off the wiring chamber through which the fixture wiring passes. The ends of each unit of the fixture are closed off by sheet-metal end plates 30 which are secured to the stamping 10 by screws indicated at 30'. The end plate, cover plate and reflector are painted or enameled white 55 to increase reflection of light. The end plates

carry cast ornamental end members 31 which extend below the level of the reinforcing members 18-18.

Various modes of installation of the lighting equipment are indicated in the drawings. In Figures 1-5 inclusive, a yoke or bridging member in the form of a bent channel member is indicated at 40. This yoke or bridging member is made of heavy material so as to be very stiff and strong. Each member is provided with welded-in bolts 41 which are adapted to pass down through holes in one of the reinforcements 16, and extend through the reflector stamping 10. The lower ends of these welded-in bolts receive nuts indicated at 42 so that the fixture body may be hung from the yokes 40. The yokes and reinforcements are preferably made of the same size channel stock and the parts offset slightly, as will be clear from Figure 2, so that a wide range of adjustment may be had without interference of one channel member with the other.

The yokes 40 have vertical side elements 43 adapted to extend down outside the fixture body and these are provided with a number of spaced holes 44, to receive bolts 45 by which angle brackets 46 may be secured at various elevations. At the right of Figure 4 an angle bracket is shown as being employed with the channel iron runner 47 carried above furring channels 48 employed for a conventional lath and plaster ceiling indicated at 49. At the left of Figure 4 the bracket 46 is illustrated as used in being secured to the angle iron 50 conventionally used with one of the well known forms of tiled acoustic ceiling 51.

The all-metal yoke and bracket arrangement indicated in full lines in Figure 4 may also be used in constructions where it is desirable to secure the bracket member directly to wood framing members, channels, and various other forms of construction. It is also possible to employ instead of the metal yoke construction, wooden cross-members 52 as illustrated in Figure 6, these being secured to the fixture body by suitable bolts. Side brackets 46 may be omitted, if desired, and the yokes 40 secured directly to overhead channel iron members 53 as indicated in Figure 7.

Whatever mode of support is employed, the opening in the ceiling is made slightly wider than the maximum width of the reflector and slightly longer so that the reflector with associated parts can be passed up through the opening. The cross-members or yokes have been previously secured in the proper position and each unit of the fixture body secured in place and tightened by the nuts 42 so as to bring the outer edges of the stiffening strips 18 against the ceiling surface. At the same time the end members 31 will be brought against the ceiling surface so that the opening provided for the fixture will be closed and finished off.

The drawings illustrate a light transmitting cover 60 in the form of prismatic plates, four of which occupy the same length as a fixture unit. These prismatic plates have side flanges 61 which rest on the inner edges 62 of the stiffening strips 18.

Where it is desired to employ the units described above in detail in continuous constructions, the completed lighting equipment employs a suitable number of units. The plates 30 and end members 31 are used only at the ends, as will be obvious. One of the units, for instance, the left one in Figure 1, will be supported by means of two cross-yokes 40-40, as illustrated. The next fixture unit to the right may be supported

by a single cross-yoke 40 on the remote end, as indicated in Figure 1 and the adjacent ends of the two units secured together by straps 63 shown more in detail in Figures 8 and 9. These straps bridge the joint at the ends of the reflectors and are secured to the reflectors by screws as indicated at 64. They retain the adjacent ends of fixture units in alignment both vertically and horizontally and carry the load of the unsuspended left hand of the center unit of Figure 1 over to the suspended right hand end of the left hand unit. This system of interconnecting the units may be extended throughout the entire length so that after the first unit is installed only one bridging member need be added for each additional unit. This reduces the cost of materials necessary in the installation and the labor required in the installation.

Where concentrated accent lighting is desired one can place at the end of a single unit or between two units, a suitable lamp box 65 with proper light controlling equipment.

Since it is obvious that the invention may be embodied in other forms and constructions within the scope of the claims, we wish it to be understood that the particular form shown is but one of these forms, and various modifications and changes being possible, we do not otherwise limit ourselves in any way with respect thereto.

What is claimed is:

1. A lighting fixture having an inverted sheet metal trough shaped reflector, fluorescent lamp sockets supported at the ends of the reflector and adapted to support fluorescent lamps extending lengthwise of the reflector, transversely extending upwardly opening channel shaped reinforcements welded to the top and sides of the reflector, relatively fixed supporting yokes of inverted channel shaped cross-section above the reinforcements and spaced slightly differently than the reinforcements so that one side of each channel shaped part may enter into the opposed channel shaped part, and bolts supporting the reflector from the yokes.
2. A recessed ceiling type fluorescent lighting fixture comprising an elongated sheet metal housing having a flat central upper portion provided with downwardly and outwardly sloping reflecting upper side portions and downwardly extending lower reflecting side portions provided with outwardly extending flanges, longitudinally extending stiffening strips secured to the flanges and extending outwardly to engage ceiling surface and inwardly for the support of a light transmitting cover, straps extending across the upper part of the housing near its ends, fluorescent lamp holders carried by the straps and projecting downwardly, a sheet-metal cover plate removably carried by the cross straps and providing a closed, shallow, wiring chamber below the upper portion of the housing, the upper portion of the housing having an elongated opening, an inverted ballast receiving box extending upwardly through the opening and secured to the housing, a ballast above the plate and secured in the box, wiring interconnecting the ballast and the lamp holders, rectilinear fluorescent lamps in the holders and below the cover plate, and a light transmitting cover carried by the flanges on the stiffening strips and below the lamps.
3. A lighting fixture as claimed in claim 2, wherein the light transmitting cover is trough shaped so as to extend below the ceiling line, and having reflector supported end members below

the ceiling line and receiving the ends of the trough shaped cover.

4. A lighting fixture as claimed in claim 2, having sheet-metal end plates across the ends of the housing to provide a lamp receiving compartment closed at its ends, and end plate carried ornamental end members extending below the ceiling line and fitted against the ends of the stiffening strips to provide a rectangular opening for the light transmitting cover.

5. A lighting fixture as claimed in claim 2, having transversely extending reinforcements conforming to the shape of the upper side portions and central portion of the housing and welded thereto intermediate the ballast receiving box and the ends of the housing.

6. A lighting fixture as claimed in claim 2, having transversely extending reinforcements in the form of upwardly opening channel strips conforming to the shape of the upper side portions and central portion of the housing and welded thereto intermediate the ballast receiving box and the ends of the housing.

7. Mounting means for a lighting fixture as claimed in claim 2, comprising fixed transversely extending supports above the housing, rods carried by the supports extending through the housing and threaded at the lower ends, and nuts threaded in the rods for securing the housing in place with the finishing strips held against the ceiling.

8. Recessed lighting apparatus comprising a plurality of identical units, each unit having an elongated inverted reflecting trough of uniform width, a fluorescent lamp ballast, and fluorescent lamps supported inside the trough and wired to the ballast, each reflecting trough carrying on its upper surface near its ends two external transverse reinforcements, straps securing adjacent ends of adjacent reflecting troughs together to keep them in alignment vertically and horizontally, transversely extending yokes secured to the

outer reinforcements of the end units and to at least one reinforcement of the intermediate units, whereby the units may be received in a ceiling opening of width equal to the width of the units and length equal to the combined length of the units, with the ceiling opening occupied by the reflecting troughs, and the row of aligned units may be yoke-supported from a superstructure.

9. Lighting apparatus as claimed in claim 8, 10 wherein the edges of the reflecting troughs carry longitudinal stiffening strips having outer edges spaced and adapted to engage the ceiling alongside the edges of the opening, and the outer ends of the end sections carry cross-members adapted to engage the ceiling at the ends of the opening.

10. Lighting apparatus as claimed in claim 8, 20 wherein the edges of the reflecting troughs carry longitudinal stiffening strips having outer edges spaced and adapted to engage the ceiling alongside the edges of the opening, and the outer ends of the end sections carry cross-members adapted to engage the ceiling at the ends of the opening, and to extend below the ceiling line, and having dished light transmitting plates carried by the inner edges of the strips and fitted between the end cross-members.
